UNITED STATES PATENT OFFICE.

JOSEPH GALLEAZZI, OF SAN FRANCISCO, CALIFORNIA.

TRANSPOSING MECHANISM FOR ACCORDIONS AND THE LIKE.

1,129,190.

Specification of Letters Patent.

Patented Feb. 23, 1915.

Application filed August 20, 1913. Serial No. 785,700.

To all whom it may concern:

Be it known that I, JOSEPH GALLEAZZI, a citizen of the United States, residing at San Francisco, in the county of San Francisco and State of California, have invented new and useful Improvements in Transposing Mechanisms for Accordions and the like, of which the following is a specification.

The object of the present invention is to 10 provide a simple and convenient transposing mechanism for accordions and the like.

In the accompanying drawings, Figure 1 is a broken front view of my improved mechanism; Fig. 2 is a horizontal section 15 thereof on the line 2-2 of Fig. 1, Fig. 3 is a vertical section of the line 3-3 of Fig. 2, certain parts being omitted for clearness of illustration; Fig. 4 is a horizontal section on the line 4-4 of Fig. 3.

20 Referring to the drawing, 1 indicates the body of an accordion, in which are pivoted, as shown on 2, the finger keys 3, rear portions 4 of which are adapted to actuate slide rods 5, the rear ends of which can slide in 25 bearings in a vertical plate 6 secured to the under side of a sounding board 7. On said slide rods are secured disks 8, which, when the slide rods are moved rearwardly by the operation of the keys, engage arms 9 of levers 11, pivoted at 12 on the under side of 30 the sounding board, said levers being normally pressed upward by springs 10, secured, as shown on 13, to the sounding board, and said levers carrying valves 14, 35 which normally close holes 16 in said sounding board. On the upper side of said sounding board are secured, by screws 17, the bases 18 of hollow or tubular posts or bearing 19, of which there is one for each 40 octave of the key-board. Rotatable in each bearing is a shaft 21, having a collar 22 secured thereto resting upon the top of said bearing, said shaft carrying at the top a disk or plate 23, formed with radially extending arms 24, which are secured, by 45 screws 26, to a flat ring 27, cemented to the upper edge of a cylindrical reed-carrier 28, and serving to close the upper ends of reed 50 chambers 29 in said carrier. In each reed-carrier there are twenty-four such chambers corresponding to the notes of two octaves. The chambers open at the outer side of the carrier, and against said openings are placed 55 reeds 31, these reeds being adapted respectively to produce the notes of one full octave, the six notes next above the octave and

the six notes next below the octave. The holes 16 in the sounding board are twelve in number, corresponding to the notes of an octave, and are arranged in a semi-circle 60 about the axis of the shaft 21 as center and on the side next the key board, so that, by the rotation of the reed-carrier, holes in the bottoms of the reed chambers can all successively register with the holes 16 in the 65 sounding board. Rigidly connected with each disk 23 and coaxially above it is a pinion 32, and all of said pinions mesh with a rack 33, so that, by the longitudinal movement of said rack, all of said pinions, and 70 consequently all of said reed-carriers, are rotated in unison.

In the normal position of the reed-carrier, the reeds that are not in use, that is, on the rear side of the reed-carrier, are, on the left, 75 from B, below the C of the octave, descending to F#, and, on the right, from C, above the B of the octave, ascending to F, so that, in each reed-carrier, the reed producing the highest note is that of F above the octave 80 and the reed producing the lowest note is that of F# below the octave. If the player wishes to transpose to a semitone higher, he moves the rack a sufficient distance to turn the pinions in a clock-wise direction, so that 85 the reed producing C# is now the lowest reed in use in each reed-carrier, and the reed producing C is the highest reed in use in each reed-carrier. By a similar, but extended, operation, the music can be transposed to 90 any key desired above the normal key of C, and by reversing the operation, that is, moving the rack to the left, to any key below the normal key.

I claim:—

1. In transposing mechanism, the combination of finger keys, individual valves therefor, a sounding board having holes arranged to be closed by said valves, rotary cylindrical reed-carriers, reeds carried thereby, said carriers being arranged to move said reeds into operative relation to said holes, and means for rotating all of said carriers in unison.

2. In transposing mechanism, the combination of finger keys, a sounding board, having holes arranged in arcs of circles, one arc for each octave of the keys, valves normally closing said holes and individually operated by said keys, rotary reed-carriers, reeds carried thereby into operative relation to the holes of the several arcs, pinions on said

reed-carriers, and a rack for rotating said pinions.

3. In transposing mechanism, the combination of a row of finger keys, a sounding board having holes arranged in semi-circular arcs, twelve holes in each arc, valves closing the respective holes, and operated by the respective keys of the corresponding octave, rotary cylindrical reed-carriers corresponding in number with the arcs, each having twenty-four open-ended reed chambers therein arranged in circular series movable

to operative relation to the several holes in the corresponding arc, reeds for the several chambers, pinions secured to said reed-carriers, and a rack arranged to rotate all of said pinions. 15

In testimony whereof I have hereunto set my hand in the presence of two subscribing witnesses.

JOSEPH GALLEAZZI.
